(57) CLAIM

I claim the ornamental design for footwear, as shown and described.

DESCRIPTION

FIG. 1 is a front perspective view of footwear, showing my new design;

FIG. 2 is a right side view thereof;

FIG. 3 is a left view thereof; and,

FIG. 4 is a top view thereof.

The broken lines are included for illustrating environmental structure and form no part of the claimed design.

1 Claim, 4 Drawing Sheets

FIG. 1

FIG. 4
